UNITED STATES PATENT OFFICE

FRANK OSBORN, OF WILEY, COLORADO, ASSIGNOR OF ONE-HALF TO GEORGE W. FINNUP, OF GARDEN CITY, KANSAS.

AUTOMATIC TEMPERATURE-REGULATOR.

1,352,685.

Specification of Letters Patent. Patented Sept. 14, 1920.

Application filed December 20, 1919. Serial No. 346,202.

To all whom it may concern:

Be it known that I, FRANK OSBORN, a citizen of the United States, residing at Wiley, in the county of Prowers and State of Colorado, have invented a new and useful Automatic Temperature-Regulator; and I do hereby declare the following to be a full, clear, and exact description of the invention, such as will enable others skilled in the art to which it appertains to make and use the same.

This invention relates to a new and useful automatic temperature regulator, by means of which the temperature of a room, or other 15 inclosure, may be automatically controlled by the position of a damper located in the smoke flue of a stove or the like.

One of the features of the invention is the provision of a thermostat, or expansion bulb, situated near the smoke flue to receive the radiant heat therefrom, the thermostat, or expansion bulb, automatically preventing the flue from reaching a temperature inconsistent with safety.

Another feature of the invention is the provision of a second thermostat, or expansion bulb, placed behind the first thermostat so as to be protected from the radiant heat of the smoke flue but exposed to the 30 heat of the room, so that this thermostat, and consequently the damper, is quickly affected by any changes of temperature in the room.

Another feature of the invention is the combination of the two thermostats so that 35 the position of the damper depends upon the resultant of the two temperatures.

Another feature of the invention is to so arrange the thermostatic elements that neither of the elements can entirely close 40 the damper, the coöperation of both being necessary.

Another object of the invention is to provide a device of the above nature, which is more sensitive to temperature changes than 45 regulators now in use.

Still another object of the invention is to provide a regulator which is of few parts, simple in operation, and one which may be readily attached to the ordinary smoke flue 50 damper now in use.

Other objects will be in part obvious and in part set forth in the detailed description which follows.

In the drawings:—Figure 1 represents an 55 elevation of the smoke flue and the thermo-

statically controlled operating mechanism attached thereto, the flue being partly broken away to show the damper.

Fig. 2 is a detail sectional view more clearly showing how the support is clamped to the flue.

Referring to the drawings in detail, 1 designates the ordinary smoke flue of a stove or the like, in which is pivotally mounted the damper 2 for controlling the 65 draft therethrough. Rigidly attached to the damper shaft is an arm 3, pivotally connected at its lower end to a link 4. Link 4 pivotally connects at its outer end with the lower end of a lever 5 mounted on 70 the standard 6, which in turn is rigidly secured to the supporting bar 7.

The support 7 may consist of two horizontal members rigidly, but removably, clamped to the smoke flue by means of bolt 75 15. Upright 8 is adjustably mounted on the horizontal supporting bar by means of a set screw 9 and carries at its upper end a thermostat or expansible bulb 10. Opposed to the expansible bulb 10 is another 80 expansible bulb 11, the two bulbs being connected by means of a rod 11a.

The expansible bulb 11 carries a tube 13, which telescopically receives the rod 12 pivotally secured to the upper end of the lever 85 5. Rod 12 is adjusted within tube 13 by means of a set screw 14.

It will be seen from the above, that the expansible bulbs may be adjusted with respect to the smoke flue, by simply loosening 90 the set screws 9 and 14, placing the bulbs in the desired position, and then setting up on the set screws.

The operation of the device is as follows. The damper is shown wide open and both 95 expansible bulbs contracted. Now, when the temperature of the smoke flue increases, the increased radiant heat therefrom will act directly on the bulb 11, causing the fluid therein to expand and move the upper arm 100 of lever 5 to the left, as shown in dotted lines on the drawing, and thereby partly close the damper. This increase in the radiant heat has had no effect on the expansible bulb 10, however, for it will be noticed 105 that this bulb is shielded from the radiant heat by being placed directly behind the bulb 11. If now, the temperature of the room rises, then the increased heat will, through the expansion of the fluid within the 110

bulb, cause a further closing of the damper. It will be evident now that the position of the damper is not controlled by the radiant heat of the smoke flue alone, or by the heat 5 of the room alone, but by the resultant of the two.

The details of construction may be subjected to alterations falling within the scope of what is claimed.

10 Having fully described my invention what I desire to claim as new and to secure by Letters Patent is:

1. A temperature regulator including a heat radiating element, a damper therefor,

15 means for controlling said damper, said means including a plurality of thermostats, one of said thermostats exposed to radiant heat from said element and shielding another thermostat from said radiant heat.

20 2. A temperature regulator including a heat radiating element, a damper therefor, means for controlling said damper, said means including a plurality of thermostats, one of said thermostats being exposed to 25 radiant heat from said element and shielding another thermostat from said radiant heat, said last named thermostat being exposed to other than radiant heat.

30 3. A temperature regulator including a heat radiating element, a damper therefor, means for controlling said damper, said means including a plurality of thermostats, one of said thermostats so constructed and arranged as to be incapable of entirely closing 35 said damper.

40 4. A device of the character described including a flue, and a damper therefor, means for controlling said damper, said means including two thermostats, one of said thermostats so constructed and arranged as to be incapable of entirely closing said damper.

45 5. A device of the character described including a heat radiating element, a damper therefor, means for controlling said damper, said means comprising a plurality of thermostats, each of said thermostats being incapable of entirely closing said damper.

50 6. A temperature regulator including a heat radiating element and a damper therefor, means for controlling said damper, said means including a plurality of thermostats, one of said thermostats being exposed to radiant heat from said element, another of said thermostats protected therefrom, one 55 of these thermostats constructed and ar-

ranged so as to be incapable of entirely closing said damper.

7. A temperature regulator including a damper, means for controlling said damper, said means including a plurality of thermostats, one of said thermostats being exposed to radiant heat and another of said thermostats shielded therefrom, each of said thermostats being independently incapable of entirely closing said damper. 60

8. A temperature regulator including a damper, means for controlling said damper, said means including two thermostats, one of said thermostats being shielded from radiant heat, the other of said thermostats 70 being exposed thereto, the construction and arrangement being such that the combined action of the two thermostats is necessary to entirely close said damper.

9. A temperature regulator including a 75 heat radiating element, a damper therefor, means for controlling said damper, said means including a plurality of thermostats, one of said thermostats exposed to radiant heat from said element and shielding another of said thermostats from said radiant heat, the construction and arrangement being such that each of said thermostats is independently incapable of entirely closing 80 said damper.

10. A device of the character described comprising a flue and a damper therefor, said flue carrying a horizontal supporting member, said supporting member carrying two uprights, one of said uprights having a 90 lever mounted thereon operatively connected with the damper, the other upright carrying a thermostatic element, said thermostatic element being connected to the lever by telescopically adjustable members. 95

11. A device of the character described comprising a flue and a damper therefor, a supporting member adjacent said flue, said supporting member carrying two arms, one of said arms having a lever mounted 100 thereon, said lever being operatively connected to the damper, the other arm slidably and adjustably mounted on the supporting member and carrying a thermostatic element, said thermostatic element being connected to said lever by telescopically adjustable members. 105

Signed at Washington, D. C., this 20th day of December, 1919.

FRANK OSBORN.
